METHOD OF AND MACHINE FOR STUFFING
UPHOLSTERY PADSWarren C. Burgess, La Grange, Ill., assignor to
Burton-Dixie Corporation, Chicago, Ill., a cor-
poration of Delaware

Application December 5, 1932, Serial No. 645,743

10 Claims. (Cl. 226—44)

This invention relates to the art of upholstery manufacture, and has reference more particularly to methods of and machines for stuffing upholstery pads with fibrous material. The machine of this application has been designed more especially for stuffing upholstery pads of a type disclosed in Letters Patent No. 1,992,603, granted to my assignee Burton-Dixie Corporation, February 26, 1935, the said pad being in the nature of a foundation pad designed to be placed between an assembly of helical springs and a finish upholstery to hide the feel of the springs. The pad of the aforesaid application comprises a slip, and a stuffing therefor consisting of a resilient body made up of an intertwined mass of long sisal fiber formed into folds or plaits that are continuous and closely packed together and disposed generally crosswise of the pad. However, the machine herein disclosed is capable of producing pads other than such foundation pads, as well as pads having a stuffing of jute, hemp, hair or any fibrous stock other than long fiber sisal, although where using short fiber stock the successive transverse folds or plaits are not continuous.

The principal object of the invention is to provide a simple and efficient machine of the character and for the purpose stated, capable of effecting the uniform and even stuffing of the pads in a rapid manner and with a minimum loss of power due to friction, and well adapted to the carrying out of a novel method of operation, under which irregularities in the stuffing are avoided, the stuffing is rendered substantially uniform in thickness and density throughout the pad, the thickness and density may be varied as desired, and the stuffing is prevented from buckling during transfer of the stuffed pad from the stuffing machine to the stitching or tacking machine.

Still other objects and attendant advantages of the invention will be apparent to persons familiar with the art from the following detailed description, taken in connection with the accompanying drawings in which I have illustrated one simple and practical form of apparatus which in practice has proved to successfully effectuate the stated purposes of the invention, wherein—

Fig. 1 is a side elevation of the machine.
50 Fig. 2 is a vertical transverse section in the plane indicated by the line 2—2 of Fig. 1.

Fig. 3 is a longitudinal vertical section in the plane indicated by the line 3—3 of Fig. 2.

Fig. 4 is a detail sectional view, enlarged, on 55 the line 4—4 of Fig. 3.

Fig. 5 is a fragmentary top plan view of the rear portion of the gang feeder, looking downwardly on the line 5—5 of Fig. 3.

Fig. 6 is a somewhat enlarged fragmentary side elevation of the cable and mandrel tube or former shown in Fig. 1. 5

Fig. 7 is an enlarged cross sectional view, on the line 7—7 of Fig. 1.

Fig. 8 is an enlarged longitudinal section, taken on the line 8—8 of Fig. 7. 10

Fig. 9 is a further enlarged vertical longitudinal section through a portion of the stuffed pad as it emerges from the former, showing the form taken by the stuffing and the anti-buckling device overlying the stuffing. 15

Fig. 10 is an enlarged inner side elevation of a vertically adjustable support for the shafts of the fiber feeding conveyor.

Fig. 11 is a vertical section on the line 11—11 of Fig. 10. 20

Referring to the drawings, on a skeleton supporting frame 10 is mounted a hopper, designated as an entirety by 11, into the upper rear portion of which is deposited the fibrous stock forming the stuffing of the pad. Fig. 3 shows a charge of this stock in the rear portion of the hopper. The fibrous stock is continuously picked up from the body of the stock in the hopper by an elevating conveyor clearly shown in Figs. 2 and 3, and comprising a pair of laterally spaced belts 12 trained over upper and lower pulleys 13 and 14 and connected by closely spaced transverse slats 15 equipped with rows of pointed teeth 16 that are forwardly inclined relatively to the direction of travel. The slats on the ascending side of the conveyor hook into and carry up a sheet of the intertwined fibers, and the surplus is scraped off and thrown back into the hopper by a reciprocating comb 17 mounted on the free ends of a pair of arms 18 that in turn are fast on a rock shaft 19 journaled across the top of the side walls of the hopper. 25

As shown in Fig. 3, the elevating conveyor is slightly inclined in an upward and forward direction, and the fibrous material carried up by the ascending limb of the conveyor is carried over the upper end of the latter and drops in a substantially continuous stream off the hooks on the descending limb, falling onto the top limb of a negative tooth feeding conveyor 20. This feeding conveyor is structurally identical with the elevating conveyor except that its teeth 20' are rearwardly inclined relatively to the direction of travel. Said feeding conveyor occupies the lower front portion of the hopper, its function being to 30

receive the fibrous stock and carry it forward and lay it in a substantially continuous strand or sheet onto a gang of toothed plunger-type feeders which reciprocate through the delivery throat 21 of the hopper, for which purpose the feeding conveyor closely overlies said feeder. The pulleys 22 and 23 on which the feeding conveyor 20 is mounted are fast on transverse shafts 24 and 25 respectively, which shafts, as shown in Figs. 10 and 11, are vertically adjustable, being journaled in bearing blocks 26 and 27 in turn mounted on an angle bar support 28, which latter in turn is adjustably mounted on a similar angle bar support 29 by means of clamp bolts 30 passed through the vertical limb of the support 29 and through vertical slots 31 in the vertical limbs of the support 28. By this means the feeding conveyor 20 can be bodily raised or lowered to adjust the same to plunger feeders with high or low teeth, the density of the layer of stock deposited on the plunger feeders depending on the relative speeds of the elevating and feeding conveyors.

As shown in Fig. 10, the bearing block 26 and an intermediate spacing block 32 on which it is supported, are adjustable lengthwise of the stationary support 28 by means of an adjusting screw 33, the purpose of which is simply to effect a proper tension on the conveyor 20.

In front of the hopper 11 and its supporting frame 10 are mounted a pair of parallel upright side frame members 34 supporting on their upper ends rails 35, on which rails is mounted, by grooved wheels or rollers 36, a flat table top 37 (see Fig. 7). Above this table 37 and narrowly spaced therefrom is a hollow former or mandrel, preferably comprising a bottom plate 38 formed with low upstanding side walls 39, and a top plate 40 formed with similar depending side walls 41 that, as clearly shown in Fig. 7, overlap the side walls 39 when the cover is in normal working position. As shown in Figs. 3 and 7, the bottom member of this former is supported on a plurality of longitudinally extending angle bar ribs 42 that in turn are rigidly attached at their rear ends to braces 43 attached at their lower ends to the supporting frame 10 and at their upper ends to a transverse channel beam 44 (Fig. 1) that also underlies the rear portion of the bottom member of the former. As best shown in Fig. 8, the forward end portions of the bottom and top walls of the former are slightly tapered toward each other, the purpose being to effect a slight narrowing or throttling of the discharge end of the former to secure a close packing or folding of the fibrous material at this point as it emerges into the slip or cover member of the pad. The inner end of this former, of course, registers with the discharge throat of the hopper.

Slidably mounted on the bottom wall of the former is a gang feeder of the toothed plunger type, commonly employed in machines of this character, and comprising, in the instance shown, a plurality of wooden strips 45 (Figs. 5 and 7) disposed side by side, connected at their rear ends by a cross head 46 and at their front ends by a transverse strip 47 (Fig. 8). On each strip 45 is mounted a metal strip 48 having on its longitudinal edges upstanding forwardly directed teeth 49; and to the under side of the cover member 40 of the former are mounted stationary metal strips 50 having on their longitudinal edges depending forwardly directed teeth 51 that lie between and overlap the teeth 49 of the feeder. The rear cross head 46 is slidably mounted at its ends on slide-ways 52 (Figs. 3 and 5), and the cross head is re-

ciprocated on said slideways by a pitman 53 connected to a crank disc 54 fast on a shaft 55 that is journaled on the frame 10.

In order to regulate the width of the stream of stock falling from the elevating conveyor onto the feeding conveyor according to the width of the pad, I provide on the inner sides of the side walls of the hopper 11 a pair of hinged depending guide plates 56 that, as shown in Fig. 3, overhang the feeding conveyor 20 and form between them a throat through which the material falls onto the feeding conveyor. The spread of these guide plates 56 is determined and fixed by simple adjusting devices shown in Fig. 2, and in detail in Fig. 4, and each comprising a rod 57 extending through a hole 58 in the side wall of the hopper and formed with a bent end 59 that lies behind the plate 56. By pushing these rods 57 inwardly, the plates 56 are moved toward each other so as to narrow the descending stream of stock; and, by retracting the rods 57, the plates 56 move apart by gravity. The plates are maintained in any adjusted position by a clamp bolt 60 slidably mounted in a sleeve 61 fast on a frame element of the hopper, the bolt and its sleeve 25 being equipped with registering holes through which the rod 57 extends, and the bolts 60 having a nut 62, by tightening which the rod is gripped and clamped in an obvious manner. Of course, any other suitable or convenient means 30 for adjusting the plates 56 and maintaining them in adjusted position may be employed.

When the cover slip of the pad is to be filled, it is first drawn onto and over the outer end portion of the former, as shown in Fig. 1, and at its open end it is connected to the rear end of the table 37 as by a pair of cords 63 and clips 64, so that, as the slip is filled and gradually pushed off the former, it draws the table along with it. It is desirable that the resistance of the table 37 to this movement be rendered as uniform as possible in order to obtain a uniform packing of the pad in point of density; and it is also desirable that the resistance of the table to this movement be capable of variation, according to whether it is desired to effect a dense or a comparatively light packing of the pad. For these purposes, the table is mounted on the rollers 36, as described; and, furthermore, the table is subjected to the influence of opposing weights 65 tending to draw the table in opposite directions, the greater weight, of course, tending to draw the table in a direction opposite to the direction of movement of the pad as the latter is being filled. Accordingly, to the forward end of the table 37 is connected a cord 66 that is led over guide pulleys 66, 68, 69 and 70 and has attached to the end thereof depending from pulley 70 a rod 71 adapted to have mounted thereon a stack of metal disc weights 72. And attached to the rear end of the table 37 is a similar cord 73 led over guide pulleys 75, 76 and 77, the lower end of said cord being attached to a rod 78 carrying a plurality of disc weights 79. The individual weights 72 and 79 are each of slight weight, so that by variously loading the weight-supporting rods 71 and 78, any desirable differential in the resultant pull of the weights on the table may be obtained.

Journaled in and across the upper forward portion of the hopper 11 is a shaft 80, on which is mounted a rotary beater 81 (Fig. 3) lying opposite and parallel to the upper portion of the descending limb of the elevating conveyor, the purpose of this beater being to knock the fibrous

material off the teeth of the elevating conveyor and cause it to drop by gravity onto the upper limb of the feeding conveyor. The front wall of the hopper 11, opposite the adjustable guide plates 56, is provided with an outwardly opening door 11', by which access may be readily had for inspection and adjustment.

The means for operating the various movable parts of the machine, other than the table 37, 10 may comprise the following. Mounted in the lower portion of the frame 10 is an electric motor 82 connected by a pulley and belt drive 83 to a shaft 84 mounted on the rear of the frame 10. Shaft 84 is connected by a pulley and belt 15 drive 85 to shaft 55, on one end of which is the crank disc 50 which, through pitman 53, operates the plunger feeder, as before described. The outer end of shaft 55 is connected by a pulley and belt drive 86 to the upper shaft 87 of the elevating conveyor, operating the latter in the 20 direction indicated by the arrows in Fig. 3. Another pulley and belt drive 88 from shaft 55 to a shaft 89 operates the oscillating comb 17 through a pitman 90 and an arm 91 fast on the 25 projecting end of the comb shaft 19. By reference to Fig. 1 it will be seen that the upper end of the pitman 90 has an adjustable connection to the arm 91, lengthwise of the latter, by which the extent of oscillation of the comb 17 may be 30 varied. By reference to Figs. 1 and 2, it will be seen that the shaft 24 of the feeding conveyor 20 is driven from the upper shaft 87 of the elevating conveyor by a chain and sprocket drive 92. The beater 81 is driven in the proper direction 35 from one end of shaft 24 by a pulley 93 on the latter, a pulley 94 on the beater shaft, and a crossed belt 95.

Briefly describing the operation of the machine, and assuming that a supply of the fibrous packing material is maintained in the hopper 11, which may be done by hand or by a suitable 40 supply conveyor (not shown), a pad slip A, open at one end, is drawn over the forward end of the former for its full length, and the sides of the open end of the slip are attached to the rear 45 end of the table 37 by the cords 63 and clips 64, as shown in Fig. 1. The machine is then started in operation, and the elevating conveyor continuously picks up the stock from the rear portion 50 of the hopper and discharges it in a continuously falling stream or thin sheet onto the upper limb of the feeding conveyor 20, the comb 17 acting to throw back any surplus or excess so as to make the feed substantially uniform, and the beater 81 operating to strip the stock from the teeth on the descending limb of the elevating conveyor and throw it directly downwardly. As before 55 mentioned, the teeth 20' on the feeding conveyor 20 preferably have a rearward inclination, which prevents the material thereon from being carried back to a point beneath the elevating conveyor; and to facilitate and insure the forward feed of the material, the top limb of the feeding conveyor 20 is pitched downwardly and forwardly, as clearly shown in Fig. 3, so that the feed is 60 assisted by gravity. As the material is conveyed by the negative tooth conveyor in a substantially uniform and continuous web or sheet onto the reciprocating toothed feeder, it is advanced by the latter in a practically continuous or unbroken sheet into and through the former, its 65 backward travel during the rearward movements of the feeder being prevented by the stationary teeth 51 on the top wall of the former, and also by the teeth on the bottom limb of the negative

tooth conveyor. In this way the material is advanced, step by step, through the former until its forward end is forced through the contracted forward end of the former, being slightly compressed thereby, into the rear closed end of the 5 slip A. Under the pressure of the material against the closed end of the slip, the latter then gradually slides off the former, onto the table 37, this movement being opposed by the superior counter weight 79 acting through the cord 13. 10 The material, when of long fiber stock, is thus placed in the cover slip in a succession of closely packed and connected plaits or folds B, Fig. 9, lying generally crosswise of the pad, as fully disclosed in my copending application hereinabove 15 identified. I have found in practice that, due to the springy character of the stock, when employing long fiber sisal or the like, the pad will buckle upwardly as it passes off the former, unless means be provided to oppose this buckling 20 tendency; and I have discovered a very simple and efficient means for this purpose, consisting of a plate or sheet, which may be of heavy cardboard or the like, identified by C, which is entered beneath the top wall of the slip, between 25 the latter and the top wall of the former, when the empty slip is first applied to the former. As the slip, undergoing the packing operation, is pushed off the former, this cardboard sheet or plate passes off with it, and, being substantially 30 the full width of the slip and fairly heavy, it effectively prevents the upward buckling or bowing of the packing, so that the loaded slip may later be bodily transferred to a stitching or tacking machine without danger of the packing becoming deformed or scrambled in the operation. The slip and the table continue to move forwardly, 35 step by step, until the slip is filled, whereupon it is released from the clips 64 and removed to the tacking or stitching machine. 40

The density of the packing can be very nicely regulated by regulating the pull on the table 37 that opposes the forward travel of the slip and the table, this being accomplished in an obvious manner by manipulation of the weights 72 and 79. 45 For instance, if a light packing is desired, the differential of the weights 72 and 79 is reduced. On the other hand, if a heavier or denser packing is desired, the weight differential is increased. The mounting of the table on the roller supports 50 practically eliminates the friction of the table as a factor affecting the density of the packing, and, as stated, the application of an adjustable weight-actuated pull at each of the opposite ends of the table enables the resistance of the table to be 55 very finely graduated.

While I have herein shown and described one specific form of the invention which, in practice, has been found to satisfactorily effectuate the 60 stated purposes and objects, I do not limit the invention to the details of structure and arrangement shown, but reserve all such variations, modifications and mechanical equivalents as fall within the spirit and purview of the claims. 65

I claim:

1. In a pad-stuffing machine, the combination of a hopper having a delivery throat, a hollow former registering with and extending forwardly of said throat, an elevating conveyor in said 70 hopper, a feeder reciprocable through said throat and former, and a toothed feeding conveyor closely overlying said feeder onto which feeding conveyor the stuffing material is dropped from said elevating conveyor and by which it is laid 75

in a substantially continuous sheet on said reciprocable feeder behind said throat.

2. In a pad-stuffing machine, the combination of a hopper having a delivery throat, a hollow former registering with and extending forwardly of said throat, an upwardly and forwardly inclined elevating conveyor in said hopper, a plunger-type feeder reciprocable through said throat and former, and a toothed feeding conveyor located in the lower forward portion of said hopper in advance of the lower portion of said elevating conveyor and closely overlying said feeder onto which feeding conveyor the stuffing material is dropped from said elevating conveyor and by which it is laid in a substantially continuous sheet on said reciprocable feeder behind said throat.

3. In a pad-stuffing machine, the combination of a hopper having a delivery throat, a hollow former registering with and extending forwardly of said throat, an upwardly and forwardly inclined elevating conveyor in said hopper, a feeder reciprocable through said throat and former, a toothed feeding conveyor located in the lower forward portion of said hopper in advance of the lower portion of said elevating conveyor and closely overlying said feeder onto which feeding conveyor the stuffing material is dropped from said elevating conveyor and by which it is laid in a substantially continuous sheet on said reciprocable feeder behind said throat, and a pair of downwardly convergent guide plates on opposite sides respectively of said hopper serving to determine the width of the falling stream of material.

4. In a pad-stuffing machine, the combination of a hopper having a delivery throat, a hollow former registering with and extending forwardly of said throat, an upwardly and forwardly inclined elevating conveyor in said hopper, a feeder reciprocable through said throat and former, a toothed feeding conveyor located in the lower forward portion of said hopper in advance of the lower portion of said elevating conveyor and closely overlying said feeder onto which feeding conveyor the material is dropped from said elevating conveyor and by which it is laid in a substantially continuous sheet on said reciprocable feeder behind said throat, a pair of guide plates hinged at their upper ends on opposite sides respectively of said hopper, and means for adjusting said guide plates toward and from each other whereby to vary the width and location of the falling stream of material.

5. In a pad-stuffing machine, the combination of a hopper having a delivery throat, a hollow former registering with and extending forwardly of said throat, an elevating conveyor in said hopper, a feeder reciprocable through said throat and former, and a feeding conveyor located in the lower forward portion of said hopper in front of said elevating conveyor onto which the material is dropped from said elevating conveyor and by which it is delivered to said reciprocable feeder behind said throat, said feeding

conveyor being equipped with teeth rearwardly inclined relatively to its direction of travel.

6. In a pad-stuffing machine, the combination of a hopper having a delivery throat, a hollow former registering with and extending forwardly of said throat, an elevating conveyor in said hopper, a feeder reciprocable through said throat and former, and a feeding conveyor located in the lower forward portion of said hopper in front of said elevating conveyor onto which the material is dropped from said elevating conveyor and by which it is delivered to said reciprocable feeder behind said throat, said feeding conveyor being equipped with teeth rearwardly inclined relatively to its direction of travel, and the upper limb of said feeding conveyor being inclined downwardly and forwardly toward said throat.

7. In a pad-stuffing machine, the combination with a stationary hollow former adapted to support a pad slip drawn thereover, and means for forcing padding material therethrough and into said slip, of a movable table beneath said former onto which the filled portion of said slip, as it is discharged from the former, comes to rest, means for attaching the open end of said slip to said table, and automatically reacting yieldable means opposing the forward travel of said table.

8. In a pad-stuffing machine, the combination with a stationary hollow former adapted to support a pad slip drawn thereover, and means for forcing padding material therethrough and into said slip, of a movable table beneath said former onto which the filled portion of said slip, as it is discharged from the former, comes to rest, means for attaching the open end of said slip to said table, and a weight attached to said table and opposing forward travel thereof.

9. In a pad-stuffing machine, the combination with a stationary hollow former adapted to support a pad slip drawn thereover, and means for forcing padding material therethrough and into said slip, of a trackway, a roller-supported table mounted on said trackway beneath said former onto which the filled portion of said slip, as it is discharged from the former, comes to rest, means for attaching the open end of said slip to said table, and differential weights acting on opposite ends of said table.

10. In a pad-stuffing machine, the combination with a stationary hollow former adapted to support a pad slip drawn thereover, and means for forcing padding material therethrough and into said slip, of a trackway, a roller-supported table mounted on said trackway beneath said former onto which the filled portion of said slip, as it is discharged from the former, comes to rest, means for attaching the open end of said slip to said table, cords attached to said table, variable differential weights suspended by said cords, and cord guiding and suspending means so disposed as to cause said weights to act in opposition to each other.
